MOISTENING APPARATUS

Fred C. Dawson, Canton, Mass.

Application January 7, 1947, Serial No. 720,664

4 Claims. (Cl. 34—155)

1

This invention relates to the moistening of sheet material such, for example, as paper, and relates more particularly to the setting of moisture setting ink which has been printed upon sheets or webs, such as paper.

Moisture setting inks are preferred for printing on the paper used for the packaging of foods, for example, for the reason that the odors and tastes which result from other inks, are not present, and the colors which may be used are more natural and pleasing to the eye. Since, however, the coloring matter in water setting ink requires moisture for its precipitation on the printed surface, the usual dryers using heat for the evaporation of the ink solvent cannot be used for speeding up the setting of the ink without damaging the ink or the paper upon which it is printed.

This invention provides for the supply of controlled quantities of moisture to sheet or web material, and provides in the printing field, for the quick setting of moisture setting inks, which utilizing this invention, can be printed upon sheets of paper such as used for the packaging of foods, cigarettes and other articles, and for other purposes, and in which the setting is completed without damage to the ink or the surface upon which it is printed.

In one embodiment of apparatus for the practice of the invention, low pressure steam is projected through one or more transverse slits upon the surface of a moving web or sheet on which is printed the ink to be set, and the steam together with air from adjacent the apparatus, is drawn into a hood and exhausted.

A feature of the invention is that the low pressure steam is maintained at the proper humidity, preferably by controlling the super-heat added by steam at a higher pressure in a pipe extending around the pipe supplying the low pressure steam to each slit.

Another feature of the invention is that the steam and the air drawn into the exhaust hood is maintained at temperatures above their dew point temperatures so that no moisture can condense and fall back upon the paper.

An object of the invention is to apply accurately controlled quantities of moisture to the surfaces of sheet or web materials.

Another object of the invention is to speed up the setting of moisture setting inks printed upon the sheet or web materials.

The invention will now be described with reference to the drawing, of which:

Fig. 1 is a plan view looking downwardly upon an ink setting unit embodying this invention;

2

Fig. 2 is a side elevation of the unit;

Fig. 3 is a sectional view along the lines 3—3 of Fig. 1;

Fig. 4 is a sectional view along the lines 4—4 of Fig. 1;

Fig. 5 is an end elevation of a portion of the unit, and

Fig. 6 is an enlarged cross-sectional view of one of the low pressure steam slits, the pipe supplying steam thereto, and the pipe supplying steam for superheating the low pressure steam.

The essence of the invention as applied to the setting of moisture setting inks, can most readily be understood with reference to Fig. 4 in which

15 the paper sheet 10 which previously has been printed with moisture setting ink is continuously moved by conventional apparatus which is not illustrated, from right to left facing Fig. 4 of the drawing through the unit 9. Low pressure steam 20 from which excess moisture has been removed as will be described, is supplied through the transversely extending, inner pipes 11 and through the nozzle slits 12 formed in the lower portions of the pipes, onto the upper surface of the sheet 10. The slits 12 extend across the entire width 25 of the sheet 10 and projects low pressure steam at a relatively high velocity upon the sheet. Steam at a higher pressure is supplied into the relatively large pipes 13 extending around the pipes 30 11.

The purpose of the steam in the pipes 13 is to add superheat to the steam in the pipes 11 so that the steam passing through the slits 12 onto the sheet 10 is maintained at the proper humidity.

35 For example, it may be maintained at a point just on the dry side of saturation. Upon contacting the cooler paper it is cooled to its saturation temperature or slightly below same whereby the proper quantity of moisture required for setting 40 the ink is condensed upon the paper surface. A large excess of moisture over that required for setting the ink is not required since it would result in unnecessary steam consumption and in undesired moisture on the surface of the paper 45 leaving the unit.

By way of example, if the paper is 100% printed, the steam pressure in the pipes 13 may be 18-20 pounds while the steam pressure in the pipes 11 may be 10 inches water gauge. If the 50 paper is 2% printed, the steam pressure in the pipes may be 5 pounds and the steam pressure in the pipe 11 may be 2 inches water gauge. As is apparent, larger steam volume and therefore higher pressures are required when the percentage of printing is greater.

The sheet metal member 14 encloses the heat insulating member 15, and forms the enclosure 21 which extends over the pipes 13, and down along the outer sides thereof to levels just above the slits 12. The sheet metal hood wall 16 is in contact with the outer surface of the member 14, and has the sheet metal hood wall 17 spaced therefrom and forming therebetween, the exhaust hood passage 18 which connects with the outlet duct 19 which is adapted to be connected to the inlet of an exhaust fan which is not illustrated.

The lower ends of the walls 16 and 17 are spaced apart to form the slots 20 therebetween, through which the steam from the slits 12, and air from the apparatus room is drawn. The steam pipes 22 are supported by the brackets 23 at each end of the hood on opposite sides of the slots 20 and adjacent the inner ends of the enclosure formed by the member 14, and are supplied with high pressure steam as will be described. The pipes 22 are heated by the high pressure steam supplied thereto and serve to heat the steam, and the air entering the slots 20 for maintaining same above the dew point of the mixture whereby no liquid droplets can condense and fall back upon the paper.

The insulation 15 is provided for preventing the inner surface of the member 14 forming the enclosure 21 from being chilled below the dew point of the steam thus preventing condensation of moisture which might drop upon the sheet 10.

The steam piping to the pipes 11, 13 and 22 will now be described with reference to Figs. 1, 2 and 6. Steam from a suitable source is supplied through the pipe 30, the valve 31 and the pipe 32 directly to the pipes 22. The pipe 30 also supplies steam through the conventional Centrifix 34 which serves to remove excess moisture from the steam, and from the Centrifix through the pressure reducing valve 36, the solenoid operated valve 35 and the piping 37 to the steam pipes 11. Steam from the Centrifix is also supplied through the pressure reducing valve 38 and piping 39 to the steam pipes 13.

The valves 36 and 38 have the hand wheels 40 and 41 respectively which are adjusted when the percentage of printing on the paper changes, the valve 36 providing the necessary steam volume through the slits 12 for setting the ink, and the valve 38 providing the necessary steam pressure in the pipes 13 for maintaining the setting steam just on the super-heat side of saturation.

The pressure of the steam supplied into the pipes 22 is not critical, and full line pressure can be used, since the purpose of these pipes is to add sufficient heat to the mixed air and steam entering the exhaust passage to prevent the mixture from being cooled below its dew point temperature.

The lower portions of the pipes 13 are connected through the pipes 45 to the inlet of the conventional condensate trap 46, the pipe 47 connecting the outlet of the trap 46 to drain. The lower portion of the Centrifix 34 is connected to the trap 49 and to drain.

The solenoid of the valve 35 in the piping 37 is wired to a conventional control at the paper drive and acts to close the valve for shutting off the steam to the pipes 11 when the paper is not moving.

By drawing air into the unit around the edges of the hood, an air seal is formed preventing the steam reflected from the paper surface from escaping into the apparatus room.

As illustrated by Figs. 1, 2, 3 and 5, the dryer

9 is supported by the bolts 50 from the channel members 51. The bolts extend through the flanges 52 of the unit and are threaded through the nuts 53 which are welded to the flanges. 5 The lower ends of the bolts extend through the lock nuts 54, the flanges 55 of the channel members 51 and the nuts 56. By adjusting the bolts 50 and the nuts thereon the spacing of the steam discharge slits 12 from the paper sheet 10 can be varied.

The proper steam pressures to be maintained in the pipes 11 and 13 can be determined through the judgment of a skilled, experienced operator, through observations of test runs through the dryer, or through charts prepared from test runs. 15 Experience so far in the practice of the invention has indicated that as previously described, for setting moisture setting inks printed on paper the applied steam should be maintained just on the dry or super-heat side of saturation for providing the proper ink setting without unnecessary steam consumption or unnecessary wetting of the paper.

Another advantage of this invention as applied 25 to the setting of ink printed on sheets of paper, is that the paper remains pliable and flexible as is desired in the packaging of foods and other materials, and does not become brittle and crack as when dried in conventional dryers.

While the invention has been described in connection with the setting of moisture setting inks 30 printed upon sheets of paper, it may be used for the moistening of unprinted sheets or webs of paper or other materials.

While the drawing illustrates the passage of a 35 continuous sheet of paper through the moistening unit, smaller, discontinuous, spaced sheets or webs of paper or other materials could be handled.

While one embodiment of apparatus for the 40 practice of the invention has been described for the purpose of illustration, it should be understood that the invention is not limited to the exact apparatus and arrangement of apparatus 45 illustrated, as modifications thereof may be suggested by those skilled in the art without departure from the essence of the invention.

What is claimed is:

1. Apparatus for applying moisture to the 50 surface of a sheet, comprising a relatively small steam pipe, said pipe having a nozzle formed in its lower surface for projecting steam from the pipe upon the sheet, a relatively large pipe extending around said pipe, means for supplying steam at a relatively low pressure into said small pipe and at a relatively high pressure into said large pipe, a hood having a wall extending over said pipes and having its ends extending downwardly alongside said pipes, said hood having a 55 second wall spaced outwardly from said wall and having its ends spaced from said ends, heat insulating material between said walls, said hood having a third wall spaced from said second wall and forming therewith end passages extending 60 from the hood ends to a common exhaust passage adapted to be connected to the inlet of a fan, said third wall providing for the entry of air into said end passages, and means adjacent the inlets to said passages for heating the air 65 and the steam drawn thereinto.

2. Apparatus for supplying moisture to the 70 surface of a sheet, comprising a steam pipe having a nozzle for projecting steam upon the sheet, means for superheating the steam in said pipe, a hood having an inner wall extending over said

pipe and having its ends extending downwardly on opposite sides of said nozzle, said hood having a second wall spaced outwardly from said wall, said walls forming therebetween a heat insulating passage, said hood having a third wall spaced outwardly from said second wall and having its lower ends spaced from the lower ends of the second wall and forming therewith end passages for exhausting the steam from said nozzle, and means adjacent the inlets to said end passages 10 for heating the steam entering same.

3. The invention as claimed in claim 2 in which the third wall is arranged to admit air at its lower ends into said end passages, and means is provided adjacent its lower ends for heating the air entering the end passages. 15

4. Apparatus for applying moisture to the surface of a sheet, comprising a steam pipe, said pipe having a nozzle on its lower surface for projecting steam from the pipe upon the sheet, means for superheating the steam in said pipe, a hood having a wall extending over said pipe and having its ends extending downwardly alongside said pipe, said hood having a second wall spaced outwardly from said wall and having its ends spaced from said ends, heat insulating 20

5 material between said walls, said hood having a third wall spaced from said second wall and forming therewith end passages extending from the hood ends to a common exhaust passage adapted to be connected to the inlet of a fan, said third wall providing for the entry of air into said end passages, and means adjacent the inlets to said passages for heating the air and the steam drawn thereinto.
